Primary Examiner — Derrick Holland(74) *Attorney, Agent, or Firm* — Morris & Kamlay LLP(57) **CLAIM**

The ornamental design for a power adapter, substantially as shown and described.

DESCRIPTION

FIGS. 1 is a perspective view of a first embodiment of a power adapter showing our new design;

FIG. 2 is a front view thereof;

FIG. 3 is a rear view thereof;

FIG. 4 is a side view thereof;

FIG. 5 is a side view thereof, opposite that of FIG. 4;

FIG. 6 is a top view thereof;

FIG. 7 is a bottom view thereof;

FIG. 8 is a perspective view of a second embodiment thereof, of which the front, rear, side, and bottom views are the same as shown in FIGS. 2-7; and,

FIG. 9 is a top view thereof.

The broken lines shown represent unclaimed subject matter and form no part of the claimed design.

The claimed design includes the trademark "nexus", owned by Google Inc.
